UNITED STATES PATENT OFFICE.

WILLIAM FINLAY, OF SCHOOLCRAFT, MICHIGAN.

WASH-BOARD.

SPECIFICATION forming part of Letters Patent No. 392,669, dated November 13, 1888.

Application filed February 14, 1888. Serial No. 261,011. (No model.)

To all whom it may concern:

Be it known that I, WILLIAM FINLAY, a citizen of the United States, residing at Schoolcraft, county of Kalamazoo, State of Michigan, 5 have invented a new and useful Wash-Board, of which the following is a specification.

This invention has for its object certain improvements below described and claimed.

In the drawings forming a part of this specification, Figure 1 is an elevation of the board; Fig. 2, a section on line 2 2 in Fig. 1; Fig. 3, a lettered detail, hereinafter described; and Fig. 4 is an enlarged lettered broken detail from Fig. 1 in perspective.

Referring to the letters marked on the drawings, B shows the side pieces; x, the top strips; b, the cap; and S, the base-strip, substantially as heretofore. The rubbing-surface of the board consists of ribbed sections a, having a tenon at the ends, which loosely fits in the channel r of the side pieces, B. (See Figs. 4 and 3.) The head-board d at each end loosely fits in said channels r and the base-heading c between the upper one of the sections a, and the board 25 d also has tenoned ends loosely fitting in channels r. Between the lower ribbed section, a, and the base-strip S are placed springs, preferably spiral springs v, in recesses or pockets in said lower section and base-strip. (See right 30 lower side of Fig. 1.) The expansive function of these springs holds the parts a c d in close contact with each other; but should any of

these parts swell the springs will yield and make room for them in the frame of the board. It is not necessary that the parts c d be loose 35 in the channels r of the side pieces, B, but preferably so. Both sides of the wash-board are alike, as shown in Fig. 2.

A wash-board thus provided with ribbed sections held in contact (in all conditions of 40 shrinking and swelling) by the springs adds greatly to the utility of wash-boards having detachable ribbed sections.

Having thus described my invention, what I claim is—

1. The wash-board frame having the channeled sides, in combination with the ribbed sections loosely fitting in said channels at the ends, and springs holding said sections in contact with each other, substantially as set forth. 45 50
2. The wash-board frame having the channeled sides, the ribbed sections, the head-board, and the base-heading, all having their ends loosely inserted in said channels, and the springs between the lower section and base-heading, substantially as set forth. 55

In testimony of the foregoing I have hereunto subscribed my name in presence of two witnesses.

WILLIAM FINLAY.
